J. A. MASCHO

FUSIBLE BOILER CHECK PLUG

Filed April 30, 1925

James A. Mascho,
INVENTOR

BY *Jack A. Mascho*
ATTORNEY

UNITED STATES PATENT OFFICE.

JAMES A. MASCHO, OF DALLAS, TEXAS.

FUSIBLE BOILER-CHECK PLUG.

Application filed April 30, 1925. Serial No. 26,842.

This invention relates to new and useful improvements in safety fuse plug devices.

In the present construction of steam boilers there is inserted in the crown sheet of the fire-box a babbitt-filled or fusible plug arranged so that when the danger point or low water stage is reached in the boiler the fusible material will be melted by the heat, releasing the water and steam, thus extinguishing the fire and preventing an explosion. It is now the common practice, after the fusible material has melted and the explosion averted, to seal up the opening in the plug by a wooden substitute filler or peg of wood, then wait until the boiler has cooled sufficiently before refilling it, which is also in this case done by means of a hand pump. The placing of the substitute plug or filler is hazardous and dangerous on account of escaping steam and hot water.

It is the object of the present invention to provide an improved means in connection with the fusible plug to close the opening made by the melting of the fusible material when or during the time the steam and water is escaping and after the fire has been extinguished, without recourse to the insertion of a wooden substitute and with minimum danger to the operator.

An important object of the invention is to provide in connection with the customary fusible plug, an arrangement whereby the plug opening may be closed manually without exposing the operator to injury, thus saving steam and water.

With the above objects in view the invention will be better and more clearly understood by reference to the following detailed description in connection with the accompanying drawings, and wherein:

Figure 1 is an elevation of a device constructed in accordance with my invention.

Figure 2 is a vertical sectional view taken on the line 2-2 of Figure 1.

Figure 3 is a cross-sectional view taken on line 3-3 of Figure 2.

Figure 4 is a plan view.

Figures 5 and 6 are detail perspective and side views of parts of the device removed from the same.

Figure 7 is a partial vertical sectional view of another form of the invention.

Figure 8 is an underside view of the plug, and

Figure 9 is a partial side view of said plug.

In carrying out the invention there is provided a substantially cone-shaped cylindrical shell 1, screw-threaded as shown in Figure 1, the lower part 2 being shaped to receive a wrench. The interior of the shell 1 is also threaded to receive a hollow plug 3, also provided with a square or hexagonal head 4.

The plug 3 represents a form of plug ordinarily employed and has an axial bore 3' filled with a babbitt core or other fusible material 5 from end to end. This plug is seated in the shell 1, as illustrated in Figure 2. The shell has a spider 6 dividing the chambers 7 and 8 and is apertured to receive the stem 9 of a valve 10, the latter having spaced vertical guides 11-11. Above the chamber 8 and communicating therewith is a passage 12 and above this is a valve seat 13 for the valve 10. This valve and stem are clearly shown in Figure 6 and in Figure 5 is a view of a supporting member or bar 14^a which is screwed onto the lower end of the valve stem to support the valve in inoperative position as in Figure 2. The bar has depending end fingers 14-14 which rest upon the top of the plug 3, so that the bar will not close the bore 3'.

In Figures 7, 8 and 9 is shown another form of the device. In this form a T-shaped key 16 is molded in the core 5 and has a horizontally directed cross-bar 16^a. The ends of this bar extend through slots 3^a in the head 4', see Figure 9. The slots 3^a are T-shaped and the ends of the bar are normally held therein. The upper end of the key supports the valve stem 9 and normally prevents its being seated in the seat 13.

In this form the supporting bar 14^a is eliminated but its equivalent, a nut 9^a may be placed on the end of the stem 9 to limit upward movement thereof. Thus the stem 9 may be released, after the core has fused, and the valve seated by moving the ends 16^a of the key 16 to register with the shanks 4^a of the slots 3^a in the head 4'.

In the operation of the device, the upper end of the shell 1 having been screwed into the crown sheet (not shown) from the fire-box, when the water is at the danger line the fusible core 5 will melt and permit the water and steam to pass down through the

passage 12, chambers 8 and 7 and bore 3' and thus extinguish the fire. When this occurs the plug 4, by means of a long handle wrench or tongs, is unscrewed, whereupon 5 the bar 14^a may fall and the valve 10 will rest in the seat 13 and thus prevent further escape of steam and water into the fire box. The boiler may now be refilled with water and a new plug inserted which will cause the 10 valve to assume its normal inoperative position.

In the form shown in Figures 7, 8 and 9, the T-shaped key 16 may be easily reached when the core 5 has melted and the ends 16^a 15 of the key 16 moved to register with the slots 4^a, thus allowing the key to drop out, whereby the valve 10 will be seated.

Various changes and modifications may 20 be made within the scope of the appended claims.

What I claim is:

1. In a boiler safety fuse plug device, a shell screw-threaded for inserting in a vertical position in a boiler, said shell having a bore and a valve seat at the upper end of said bore, a valve for engaging said seat normally supported above it, means for supporting said valve in its normal position, a plug screw-threaded into the lower end of the shell, said plug having a bore extending therethrough, and a fusible core in the bore of the plug, the plug carrying means for supporting the valve in its normal position after the core has melted.

2. In a boiler safety fuse plug device, a shell screw-threaded for insertion in a vertical position in a boiler, said shell having a bore and a valve seat at the upper end of its bore, a spider extending across the bore within the shell, a valve normally held above the seat of the shell, a stem depending from the valve within the shell and extending through the spider, means on the lower end of the stem engaging the spider for limiting the upward 40 displacement of the valve and stem, and a plug screw-threaded into the lower end of

the shell below the spider and having a fusible core, the shell and parts carried thereby being bodily removable from the boiler.

3. In a boiler safety fuse plug device, a shell screw-threaded for insertion in a vertical position in a boiler, said shell having a bore and a valve seat at the upper end of the bore, a spider extending across the bore, a valve normally held above the seat of the shell, a stem depending from the valve and extending through the spider, means on the lower end of the stem engaging the spider for limiting the upward displacement of the valve stem, and a plug screw-threaded into the lower end of the shell below the spider and having a fusible core, the plug carrying means for supporting the valve in its normal position after the core has melted.

4. In a boiler safety fuse plug device, a shell screw-threaded for inserting in a vertical position in a boiler, said shell having a bore and a valve seat at the upper end of said bore, a valve for engaging said seat normally supported above it, means for supporting said valve in its normal position, and a plug removably mounted in the lower end of the shell and having a fusible core, the valve supporting means supporting the valve in its open position after the fusing of the core of the plug and being removably supported in the plug so as to be removed for closing the valve.

5. In a boiler safety fuse plug device, a shell screw-threaded for insertion in a vertical position in a boiler, said shell having a bore and a valve seat at the upper end of said bore, a valve for engaging said seat, a stem depending from the valve, a plug removably mounted in the lower end of the shell and having a fusible core, and a key removably mounted in the plug and supporting the valve stem.

In testimony whereof I have signed my name to this specification.

JAMES A. MASCHO.
